CLAIM

The ornamental design for a golf tee as shown and described.

DESCRIPTION

FIG. 1 is a top perspective view of a golf tee showing the new ornamental design;

FIG. 2 is a front view thereof, wherein the golf tee has 360° rotational symmetry;

FIG. 3 is a top view thereof; and,

FIG. 4 is a bottom view thereof.

The broken lines in the drawings illustrate portions of the golf tee that form no part of the claimed design.
